(57) **CLAIM**

The ornamental design for a packaging container, as shown and described.

DESCRIPTION

Fig. 1.1 is a Perspective view showing the Front, Bottom, and Right sides of the packaging container showing the new design;

Fig. 1.2 is a Perspective view showing the Front, Bottom, and Left sides thereof;

Fig. 1.3 is a Front view thereof;

Fig. 1.4 is a Back view thereof;

Fig. 1.5 is a Top view thereof;

Fig. 1.6 is a Bottom view thereof;

Fig. 1.7 is a Right view thereof; and

Fig. 1.8 is a Left view thereof.

The broken lines in the drawings illustrate portions of the packaging container that do not form part of the claimed design. The dotted-dashed lines in the drawings indicate the boundary between the claimed area and the unclaimed area of the packaging container.

1 Claim, 8 Drawing Sheets
